CLAIM

The ornamental design for a gas sediment trap, as shown and described.

DESCRIPTION

FIG. 1 is an isometric view of the gas sediment trap, embodying the claimed design;

FIG. 2 is a right plan view thereof;

FIG. 3 is a left plan view thereof;

FIG. 4 is a front plan view thereof;

FIG. 5 is a rear plan view thereof

FIG. 6 is a top-down plan view thereof; and,

FIG. 7 is a bottom-up plan view thereof.

The broken lines shown in the drawings illustrate portions of the gas sediment trap that form no part of the claim.

1 Claim, 7 Drawing Sheets
